ELECTRIC INSECT CONTROL UNIT

Frank L. Giordano, Stone Mountain, Ga., assignor to The National Ideal Company, Stone Mountain, Ga., a corporation of Ohio

Filed Nov. 28, 1967, Ser. No. 9,567

Term of patent 14 years

(Cl. D22—19)

FIG. 1

FIG. 2

FIG. 3-

FIG. 4-

FIG. 5-

FIG. 1 is a perspective view showing an electric insect control unit embodying my new design;

FIG. 2 is another perspective view of the electric insect control unit shown in FIG. 1;

FIG. 3 is a top plan view of the electric insect control unit shown in FIG. 1;

FIG. 4 is a side view of the electric insect control unit shown in FIG. 1, the other side not shown being substantially the same; and

FIG. 5 is an end view of the electric insect control unit shown in FIG. 1, the other end not shown being substantially the same.

I claim:

The ornamental design for an electric insect control unit, as shown and described.
